UNITED STATES PATENT OFFICE.

HENRY P. HILBERT, OF CINCINNATI, OHIO.

PAPER COATING OR TREATING MACHINE.

No. 873,126.

Specification of Letters Patent.

Patented Dec. 10, 1907.

Application filed July 23, 1906. Serial No. 327,341.

To all whom it may concern:

Be it known that I, HENRY P. HILBERT, a citizen of the United States, residing at Cincinnati, in the county of Hamilton and State 5 of Ohio, have invented new and useful Improvements in Paper Coating or Treating Machines, of which the following is a specification.

This invention relates to a paper coating or 10 treating machine and especially for rendering paper water proof, or for applying paraffin wax to one or both sides of a paper web. At times, however, the machine may be used for applying oil, petrolatum, crude or refined, 15 and other material.

One of the main advantages of the present machine is that it will wax or treat the grades of paper from the weakest tissue paper to heavy tag-board. The paper is drawn from 20 the wound roll preferably by two draw rolls at the same or regular speed throughout, or without any variation in the feed thereof to the waxing or treating parts of the mechanism. The wax or other material is evenly 25 distributed to the paper irrespective of the irregular thickness or inequality of caliper of the web.

The mechanism includes among other features a re-winding element having a frictional device which is readily adjustable to 30 vary the condition of the wound roll of treated paper and to have such roll either loose or tight. Further, to momentarily change the speed of the transfer rolls engaged by the 35 web to regulate the amount of wax or other material applied to the paper. The web of paper after receiving the material or wax from the transfer rolls is caused to engage or travel over guide rolls of a particular form or 40 of slatted construction which causes the web to adhere thereto and create a vacuum with respect to the web and prevent the latter from wrinkling or in any other manner becoming irregularly distorted.

Many other structural advantages will be 45 herinafter set forth and the primary object of the invention is to provide a comparatively simple organization of coating elements which will render the application of 50 wax or other material to a paper web of any thickness or quality between a minimum and maximum thickness in an effective and expeditious manner.

In the drawings, Figure 1 is a side elevation 55 of a machine embodying the features of the invention and showing the same broken

away in part. Fig. 2 is an elevation looking towards opposite side of a part of the machine. Fig. 3 is a top plan view partially broken away. Fig. 4 is a longitudinal vertical section of a portion of the machine on an enlarged scale. Fig. 5 is a longitudinal vertical section on an enlarged scale of one of the distributing or calender rollers, together with the attachments therefor. Fig. 6 is an enlarged longitudinal vertical section of the friction mechanism co-operating with the re-winding device for the web.

Similar characters refer to like parts throughout the several views.

The numeral 1 designates a frame of suitable construction comprising the necessary parts for the support of the elements which will be hereinafter set forth and including standards or uprights 2 and rearwardly projecting sills or beams 3 having supporting pillars or analogous devices 4 at their rear extremities. It will be understood that the frame will be generally organized and shaped to facilitate the application of the co-operating elements and is subject to variations in dimensions and proportions within the skill of the ordinary mechanic to arrive at the result sought. In the front end of the frame a roll spindle 5 is removably held and is 85 adapted to contain a web 6 of paper which is regularly rolled thereon and may be taken directly from a paper making machine and positioned in the frame as clearly shown by Fig. 1. It is obvious that this spindle 5 may 90 be provided with any of the attachments now commonly employed in connection therewith for winding thereon and unwinding therefrom a paper web, or to control the degree of slackness or tautness of the coils of 95 the web, and the most improved devices for this purpose will be employed and the invention is not confined to any particular mechanism at this point. Adjacent to what may be termed the feeding roller and comprising 100 the spindle 5 are a pair of draw rollers 7 and 8, the draw roller 7 being solid and of metal, and the draw roller 8 preferably having a wooden core covered with felt or provided with a yielding surface. The roller 8 is 105 slightly movable in its bearings and is adjustable through the medium of an eccentric shaft 9 arranged adjacent thereto to vary the pressure thereof with respect to the roller 7. The rollers 7 and 8 are located in advance of 110 the front extremity of a tray 10 for receiving paraffin wax or other material and having

a steam coil 11 in the bottom thereof which is suitably supplied with steam to maintain the wax or material in proper condition for application to the paper web. This tray 10 is held between the opposite sides of the frame and has mounted in the rear portion thereof a transfer roll 12, see Fig. 4, said roll 12 being mounted on a shaft 13. Vertically below the shaft 13 is a shaft 14 having thereon a second transfer roll 15 which is disposed in one extremity of a second tray 16 for holding wax or other material and also provided with a steam coil in the bottom thereof similar to the tray 10. The tray 16 is supported by suitable hangers 17 and 18 attached to the frame and both trays are held in fixed position or always maintain the same relation with respect to the transfer rolls coöperating therewith.

20. The web of paper in passing from the feeding roller at different points throughout the length of the machine or throughout the course of run of the said web, engages directing or guiding rollers 19, 20 and 21, the roller 19 being located below the draw rollers, the roller 20 between the draw rollers and the transfer roll 15, and the roller 21 between the two transfer rolls 12 and 15, as clearly shown by Fig. 4. Other similar guiding or directing rollers will be hereinafter referred to and all of similar construction and embodying solid heads 22 of wood secured on a spindle 23, the heads being connected by slats 24 with openings therebetween as at 25, and thereby providing means for causing the paper web to closely adhere thereto or set up a vacuum in conjunction with said rollers to prevent the formation of wrinkles or other irregular distortions of the web as it traverses the different parts of the machine. The paper web from the feeding roller first passes down and under the guiding or directing roller 19 and thence upwardly between the draw rollers 7 and 8, and after passing over the metal roller 7 it runs under and closely contacts with the guiding roller 20, and then over the transfer roll 15 coöperating with the lower tray 16, and passes over the rear of the guiding roller 21 from the transfer roll 15, and then up to and over the upper portion of the transfer roll 12 in the upper tray 10. Between the uprights 2 a series of hollow distributing rollers 26 are mounted and are supplied with steam and have other connections which will be more fully hereinafter set forth. The web after leaving the upper transfer roll 12 passes under the lowermost distributing roller 26 and regularly in reverse directions traverses the remaining ones of the stack of distributing rollers and finally passes off rearward from the uppermost distributing roller over a guiding roller 27 rotatably supported by the sills or beams 3 and then down under and in contact with a guiding roller 28 also held by the beams or sills 3 and then up-

wardly and over a guiding roller 29 on the rear terminals of the sills or beams or downwardly to a guiding roller 30 having bearings at its ends in supporting devices 31 located adjacent to the lower terminals of the pillars 70. 4. From the guiding roller 30 the web 6 returns in an upward direction to the front of the machine and first passes over a guiding roller 32 supported by the lower portions of the sills or beams 3 and also over a guiding 75 roller 33 similarly held and located in advance of the roller 32 and over a re-winding shaft or spindle 34 supported by the rear extremity of the main frame in rear of the lower tray 16 and having in connection therewith mechanism for regulating the speed of rotation thereof to control the slack or taut condition of the re-winding web and which mechanism will be more fully hereinafter referred to. The web in passing over the distributing rollers 26 has the paraffin wax or other material regularly spread throughout the same, in view of the fact that the said distributing rollers are maintained at a constant degree of heat by the steam fed thereto. 90 The sills 3 carrying the guiding rollers 27, 28, 29, 32 and 33 together with the guiding roller 30 may be properly stated as providing a cooling extension and also serving to give the web after treatment a sufficient run to effect 95 the drying of the material applied to the web, before it is re-wound on the spindle 34. To facilitate the drying of the web as it passes over this cooling extension of the machine, it is subjected to an air blast from a suitable 100 blower and fed to a pipe 35 which will be tapered to such a degree as to equalize the pressure throughout the length thereof, and provided with three branches 36 depending therefrom and extending across the machine 105 to the center line at intervals, the mouth 37 of each branch being tapered to an oblong funnel and the air delivered therefrom directly on and along with the web and on both sides.

The foregoing description relates to the main elements of the invention and includes many of the essential features, and the operative mechanism or the devices controlling the movement of the several parts just explained will now be set forth. Between the upper terminals of the uprights 2 a driving pulley 38 is arranged and is operated by a belt 39 from a suitable line-shaft. This pulley 38 will be preferably of the double type 115 and also engaged by a belt 40 running downwardly and rearwardly of the web re-winding mechanism. The pulley or the shaft carrying the same will also have thereon a sprocket-wheel 41 preferably having fifteen teeth and traversed by a chain belt 42 which runs downwardly and engages a sprocket wheel 43 coöperating with the distributing roller 26 next to the uppermost of the series 120 of said rollers and preferably provided with 125 said rollers and preferably provided with 130

twenty-five teeth, this sprocket wheel 43 controlling the rotation of the distributing rollers. These distributing rollers receive their motion directly from the driving pulley 5 and also serve in a manner which will be presently explained to operate the remaining parts of the machine. From a sprocket wheel 44 coöperating with the lowermost distributing roller a chain belt 45 runs to a sprocket wheel 46 connected to the driving roller 7. Connected with the distributing roller 26 next above the lowermost of the series of said rollers is a sprocket wheel 47 preferably having nine teeth and traversed by a chain belt 48 which runs upwardly over a sprocket wheel 49 held on a shaft 50 and preferably having forty teeth therein. On the shaft 50 a sprocket wheel 51 is removably applied and is traversed by a chain belt 52 which extends downwardly and engages a sprocket wheel 53 connected to the spindle or shaft 13 of the transfer roll 12. This spindle or shaft 13 also has thereon a pulley 54 and on the spindle or shaft 14 of the lower transfer roll 15 a pulley 55 is secured. The pulleys 54 and 55 have a crossed belt 56 trained thereover to cause the transfer rolls 15 and 12 to have a proper direction of rotation with respect to the movement of the web of paper.

The amount of melted paraffin or other material applied to the web of paper moving over the transfer rolls 15 and 12 is dependent solely upon the rapidity of rotation of the said rolls and the degree of rotation of these rolls may be readily varied by moving or changing the sprocket wheel 51 or replacing the same by sprocket wheels having different number of teeth. Let it be presumed, for example, that the sprocket wheel 51 as shown is provided with seven teeth and the sprocket wheel 53 with thirty teeth. With this proportion the transfer rolls will run three revolutions per minute. If the seven-toothed sprocket wheel 51 is removed and replaced by a twenty-four-toothed wheel then the transfer rolls will run thirteen revolutions per minute. From the foregoing it will be understood that the faster the transfer rolls rotate the greater will be the amount of wax or other material picked up from the trays 16 and 10 and delivered to the paper, and that the quantity of material applied may be regulated at will by changing the sprocket wheel coöperating with the spindle or shaft 50. The sprocket wheel 51 may be varied between a seven-toothed wheel and a twenty-four-toothed wheel. It will also be observed that the drawing rollers are driven at a rate of speed in proportion to the rotation of the distributing rollers and that such speed will be uniform; the object being to have the paper web travel at the same speed at all times, but the speed of the transfer rolls may be modified as just explained to

apply a greater or lesser amount of melted wax or other material to the web.

Each of the distributing rollers is provided with a stuffing box 57 as shown by Fig. 5, said stuffing box being preferably of the type known as the "Connelly".

At regular intervals several chain belts will be engaged by belt tightening idlers 58, 59, 60 and 61. Furthermore, it will be seen that the machine may have transfer rolls of considerable diameter used therein and co-operate with the same trays and also the other rollers may be modified in dimensions and general proportions with respect to each other as may be found necessary.

The re-winding spindle 31 is provided with frictional mechanism for controlling the tight or loose coiling of the web thereon, such frictional mechanism being illustrated on an enlarged scale by Fig. 6. This frictional mechanism consists of a hand-wheel 62 secured to a screw 63 movably engaging a screw-threaded socket 64 in the outer end of the spindle 34, said screw having one extremity of a yoke 65 attached thereto and also to a sleeve 66 surrounding the shaft inside of an outer bearing 67 held by a bearing yoke 68 secured to the adjacent side portion of the frame, as clearly shown by Fig. 3.

The sleeve 66 contacts with the outer end of a hub 69 carrying a friction disk 70 at its inner end and rotatable with the shaft when proper adjustment is made through the medium of a second friction disk 71 fast on the shaft, both friction disks having contiguous faces with angular offsets or beveled edges as at 72 to provide a snug interfitting of the contiguous faces of the two disks. The contacting face of the disk 71 is provided with a leather covering 73 to render the frictional contact thereof effective.

Between an inner bearing 74 for the spindle 34 and the hub 75 of the adjacent disk 71 and also between the sleeve 66 and the adjacent end of the hub 69 of the disk 70, anti-frictional bearing devices or bolts 76 are interposed to render the parts sensitive in their operations as well as obviate wear between the several parts at the points set forth. On the hub 69 a pulley 77 is mounted and is engaged by the belt 40 running from the driving pulley 38. This pulley 77 is formed with an inner seat or cavity 78 and incloses a spring 79, one terminal of the spring being attached to the hub 69 and the other terminal to the pulley 77.

The object of the use of this spring is to release the pulley when the friction mechanism through the actuation of the hand-wheel 62 and screw 63 is operated to release the friction disk 70 from the friction disk 71, it being seen that as the spring is being wound tight in view of the fact that it is secured to opposite extremities respectively to the hub 69 and the pulley 77, that the said hub will be rotated vertically and the rotary

contact thereof effective. Between an inner bearing 74 for the spindle 34 and the hub 75 of the adjacent disk 71 and also between the sleeve 66 and the adjacent end of the hub 69 of the disk 70, anti-frictional bearing devices or bolts 76 are interposed to render the parts sensitive in their operations as well as obviate wear between the several parts at the points set forth. On the hub 69 a pulley 77 is mounted and is engaged by the belt 40 running from the driving pulley 38. This pulley 77 is formed with an inner seat or cavity 78 and incloses a spring 79, one terminal of the spring being attached to the hub 69 and the other terminal to the pulley 77.

The object of the use of this spring is to release the pulley when the friction mechanism through the actuation of the hand-wheel 62 and screw 63 is operated to release the friction disk 70 from the friction disk 71, it being seen that as the spring is being wound tight in view of the fact that it is secured to opposite extremities respectively to the hub 69 and the pulley 77, that the said hub will be rotated vertically and the rotary

contact thereof effective. Between an inner bearing 74 for the spindle 34 and the hub 75 of the adjacent disk 71 and also between the sleeve 66 and the adjacent end of the hub 69 of the disk 70, anti-frictional bearing devices or bolts 76 are interposed to render the parts sensitive in their operations as well as obviate wear between the several parts at the points set forth. On the hub 69 a pulley 77 is mounted and is engaged by the belt 40 running from the driving pulley 38. This pulley 77 is formed with an inner seat or cavity 78 and incloses a spring 79, one terminal of the spring being attached to the hub 69 and the other terminal to the pulley 77.

The object of the use of this spring is to release the pulley when the friction mechanism through the actuation of the hand-wheel 62 and screw 63 is operated to release the friction disk 70 from the friction disk 71, it being seen that as the spring is being wound tight in view of the fact that it is secured to opposite extremities respectively to the hub 69 and the pulley 77, that the said hub will be rotated vertically and the rotary

motion of said hub will be transmitted through the disk 70 to the disk 71. By means of this frictional mechanism, as before stated, the spindle 34 is caused to wind 5 the web either slack or taut as may be found necessary, and the variation as to winding can be accomplished without stopping the machinery or disturbing the assemblage of the several parts in connection with the said 10 spindle.

It will be understood that the driving pulley organization operated from the line-shaft, as hereinbefore set forth, will be equipped with fast and loose pulleys to suitable belt shifting means to throw the machine into and out of operation when found 15 desirable. The distributing rollers are also supplied with steam from a suitable steam pipe 80 attached to a steam supply source 20 and each roller has a T-connection 81 provided with a valve 82 as clearly shown by Fig. 2, and whereby the steam may be admitted to or shut off from the several rollers as found necessary, or different quantities of 25 steam may be admitted to the several rollers, as it may be necessary to have the rollers hottest nearest the bottom and gradually decreasing in temperature towards the top of the stack of rollers. The steam supply pipe 30 80 also has a valve 83 therein which is operative to entirely shut off the steam from the distributing rollers. Other accessories not described will be supplied at points where found necessary and within the purview of 35 mechanical skill.

What I claim is:

1. In a machine of the class specified, the combination of upper and lower trays, transfer rolls coöperating with said trays, drawing 40 rollers, a spindle for holding a web of paper, slatted guiding rollers between the spindle for holding the web of paper and the drawing rollers, and between the latter and the transfer rolls, heated distributing rollers, and cooling 45 means for treating the web of paper after it leaves the heated distributing rollers.

2. In a machine of the class set forth, the combination with a paper supporting spindle, drawing rollers adjacent to the said spindle, 50 one of the rollers having a flexible covering and the other solid metal, means for moving

one roller toward the other, a tray for containing a liquid material, a transfer roll disposed in upper relation to the tray to raise the liquid therefrom, a stack of heated distributing rollers arranged above the tray, and air feeding devices for cooling the paper web after it leaves the distributing rollers. 55

3. In a machine of the class described, the combination of paper web feeding mechanism, means for applying a liquid coating to the paper, a stack of heated distributing rollers, guide rollers associated therewith, means for actuating the distributing and guide rollers, means for causing the web of 60 paper to run slack or taut, an extended conveying means having guiding devices, and means for supplying an air blast to the web of paper when the same passes over the conveying means. 70

4. In a machine of the class described, the combination with a paper supporting spindle drawing rollers adjacent to the spindle, one of the rollers having a flexible covering and the other solid metal, means for moving one 75 roller towards the other, a tray for containing a liquid material, a transfer roll disposed in upper relation to the tray to raise the liquid therefrom, a stack of heated distributing rollers arranged above the tray, and air feeding devices for cooling the paper web 80 after it leaves the distributing rollers. 80

5. In a machine of the class described, the combination of a paper web feeding mechanism, means for applying a liquid coating to 85 the paper, a stack of heated distributing rollers, guide rollers, associating therewith, means for actuating the distributing and guide rollers, means for modifying the speed of the feeding mechanism without changing 90 the speed of the means for applying the coating material, a conveying means having guiding devices, and means for cooling the paper when passing over the conveying means. 95

In testimony whereof, I affix my signature in presence of two witnesses.

HENRY P. HILBERT.

Witnesses:

FREDERICK J. WERNER,
J. W. JOHNSON.
